UNITED STATES PATENT OFFICE

114,598

DESIGN FOR A DISINFECTOR

Roy A. Myers, St. Paul, Minn.

Application February 27, 1939, Serial No. 83,221

Term of patent 3½ years

To all whom it may concern:

Be it known that I, Roy A. Myers, a citizen of the United States, residing at St. Paul, in the county of Ramsey and State of Minnesota, have invented a new, original, and ornamental Design for Disinfectors, of which the following is a specification, reference being had to the accompanying drawing, forming part thereof.

Fig. 1 is a front elevational view of a disinfecter showing my new design.

Fig. 2 is a side elevational, and

Fig. 3 is a top plan view thereof.

I claim:

The ornamental design for a disinfecter, as shown.

ROY A. MYERS.
